(57) **CLAIM**

The ornamental design for a golf tee holder, as shown and described.

DESCRIPTION

FIG. 1 shows a front elevational view of the golf tee holder; FIG. 2 shows a back elevational view of the golf tee holder; FIG. 3 shows a right side elevational view of the golf tee holder;

FIG. 4 shows a left side elevational view of the golf tee holder; FIG. 5 shows a top plan view of the golf tee holder;

FIG. 6 shows a bottom plan view of the golf tee holder; and, FIG. 7 shows a front, right side perspective view of the golf tee holder with a golf tee inserted therein.

The broken line portions are drawn for environmental purposes only and form no part of the claimed design.
